Primary Examiner — Holly Baynham*Assistant Examiner* — Rhea Shields(74) *Attorney, Agent, or Firm* — Schwegman Lundberg & Woessner, P.A.(57) **CLAIM**

The ornamental design for a fusion bone plate, as shown and described.

DESCRIPTION

FIG. 1 is a top view of a fusion bone plate shown on a metatarsal bone of the foot to illustrate size and use of the fusion bone plate.

FIG. 2 is a top view of the fusion bone plate, shown with removable guides inserted into screw holes of the fusion bone plate.

FIG. 3 is a bottom view of the fusion bone plate, shown with removable guides inserted into screw holes of the fusion bone plate.

FIG. 4 is a top view of the fusion bone plate.

FIG. 5 is a bottom view of the fusion bone plate.

FIG. 6 is a first end view of the fusion bone plate.

FIG. 7 is a second end view of the fusion bone plate.

FIG. 8 is a first side view of the fusion bone plate.

FIG. 9 is a second side view of the fusion bone plate; and, FIG. 10 is a perspective view of the fusion bone plate.

In the drawings, the broken lines are for the purpose of illustrating environment only and form no part of the claimed design.
